UNITED STATES PATENT OFFICE.

STEPHEN B. GILHULY, OF LONG BRANCH, NEW JERSEY.

DESIGN FOR A BICYCLER'S BAG.

SPECIFICATION forming part of Design No. 22,057, dated December 13, 1892.

Application filed July 25, 1892. Serial No. 441,201. Term of patent $3\frac{1}{4}$ years.

To all whom it may concern:

Be it known that I, STEPHEN B. GILHULY, a citizen of the United States, residing at Long Branch, in the county of Monmouth and State 5 of New Jersey, have invented and produced a new and original Design for a Bicycler's Bag, of which the following is a specification, reference being had to the accompanying drawing, forming part thereof, in which the 10 bag appears in perspective.

The leading feature of the design consists in a bag having the form of a scalene triangle truncated at its most acute angle.

In the drawing, A is the bag, in the form of

a truncated scalene triangle, whose wide end ¹⁵ *a* and narrow end *b* are parallel, while the angle of the lower edge *c* is considerably greater than that of its upper edge *d*, all of the lines described by said ends and upper and lower edges being straight or uninterrupted. ²⁰

Having thus described my invention, what I claim is—

The design for a bicycler's bag, as herein shown and described.

STEPHEN B. GILHULY.
